[57] CLAIM

The ornamental design for turning block for glass panels or the like, substantially as shown and described.

DESCRIPTION

FIG. 1 is a side elevational view of the turning block for glass panels or the like in accord with my new design; FIG. 2 is a right end elevational view thereof, the left end elevational view being substantially identical thereto;

FIG. 3 is a top plan view thereof;

FIG. 4 is a bottom plan view thereof;

FIG. 5 is an enlarged cross sectional view taken along line 5—5 of FIG. 3; and

FIG. 6 is a view substantially identical to FIG. 5 but with the block rotated 90° clockwise on its pivot, with the rubber pad and support plate being shown in end elevation.
